H. T. CRONK,
SYSTEM FOR FLUSHING CLOSET BOWLS,
APPLICATION FILED NOV. 25, 1914. RENEWED FEB. 23, 1918.

Patented Nov. 5, 1918.

UNITED STATES PATENT OFFICE.

HARRISON TAYLOR CRONK, OF NEW YORK, N. Y., ASSIGNOR TO CRONK-SALTER COMPANY, OF NEW YORK, N. Y., A CORPORATION OF NEW YORK

SYSTEM FOR FLUSHING CLOSET-BOWLS.

1,284,181.

Specification of Letters Patent.

Patented Nov. 5, 1918.

Application filed November 25, 1914, Serial No. 873,920. Renewed February 23, 1918. Serial No. 218,900.

To all whom it may concern:

Be it known that I, HARRISON TAYLOR CRONK, a citizen of the United States, and a resident of the borough of Manhattan, in the city, county, and State of New York, have invented certain new and useful Improvements in Systems for Flushing Closet-Bowls, of which the following is a specification.

- 10 My invention relates to a system for flushing water-closet bowls and while the invention is generally applicable to water closet bowls, urinals and flushing receptacles of any character, it is particularly applicable 15 to such devices when used on railroad cars, in office buildings and similar places where the conservation of flushing fluids is of economical importance.

The primary object of the invention is to 20 provide an improved form of bowl the interior of which can be effectively flushed with a minimum amount of flushing fluid.

I attain this object broadly by directing a pair of flushing streams along the curved 25 sides of a bowl from a position in advance of the center of defilement toward a restricted or tunnel shaped outlet to cause a whirling action sufficient to raise the heavy refuse and drown the light refuse toward the core 30 of the moving stream.

Among the other objects incidental to the primary object above recited, is to obtain the maximum force of fluid ejected into the bowl possible with the feed pressure used, 35 and to cause said streams to assume an ejecting form best suited to make the desired whirl with the least possible amount of fluid.

I attain these objects by reducing the cross-sectional area of the flushing fluid outlets from the similar area of the feed pipe 40 supplying the outlets, and by designing the outlets so that the flushing fluid as it is ejected along each of the inner sides of the bowl shall have a broad flat solid form under considerable pressure.

It is yet another object of the invention to provide a bowl having such an arrangement of parts and having the flushing fluid so directed therethrough that any light floating 45 refuse matter is damped and the whole mass of refuse and water quietly whirled from the bowl without splashing.

I attain this object broadly by constructing a bowl the interior of which is formed 50 with rounded flowing lines leading to a fun-

nel shaped outlet and in which the bottom is slightly concaved from front to rear to form a well beneath the center of defilement and the flushing water is fed thereto in the form of two diverging and fan shape streams 60 having a movement downwardly and inwardly toward the center of defilement and laterally of the general movement of the streams toward the rear outlet. Further I feed practically all of the flush water longitudinally down the long sweeping curved bottom from the front of the bowl in a direct line or substantially direct line to the rear outlet.

Various other objects and advantages of 70 the invention will be in part obvious from an inspection of the accompanying drawings, and in part will be more fully set forth in the following particular description of one form of mechanism embodying my invention. The invention also consists of certain new and novel features of construction and combination of parts hereinafter set forth and claimed.

Referring to the accompanying drawings: 80

Fig. 1 is a longitudinal vertical sectional view taken through a preferred embodiment of my invention, taken on the irregular line 1-1 of Fig. 2;

Fig. 2 is a horizontal sectional view taken 85 on the line 2-2 of Fig. 1 looking down into the bowl;

Fig. 3 is a transverse vertical sectional view taken on the line 3-3 of Fig. 1 looking in the direction indicated by the arrows; 90

Fig. 4 is a detailed horizontal sectional view taken on the line 4-4 of Fig. 1, and

Fig. 5 is a similar view taken on the line 5-5 of Fig. 1.

In the drawings, there is shown a bowl, 1, 95 preferably of greater length from front to rear than the hoppers now in general use. This bowl is provided with a top ledge forming a seat, 2, which also constitutes a flushing rim, and with inwardly projecting side ribs, 100 3, positioned slightly below the seat. The hopper has a bottom, 4, which considered longitudinally from front to rear, is in the form of a compound curve, the front portion of which has a radius of small diameter and 105 the rear portion of which is horizontally inclined and has a radius of relatively large diameter, the two portions forming a long sweeping curve of that form which will give the greatest velocity to the water fed down 110

the front portion. This rear portion is slightly concaved to form a well 5 at the center of infilement of the bowl indicated by the line 3-3 and terminates at its rear in a 5 dam 6. A vertically inclined outlet 7 of relatively large cross-sectional area is positioned at the rear of the bowl adjacent the dam to receive the refuse swept from the well over the dam. A continuous side wall 8 10 has a front portion 9 which bellies outward and rounds with a continuous curve into the bottom so that the forward portion of the bowl is substantially in the form of the end portion of an oblate spheroid.

15 The rear portion of this side wall is formed of substantially straight converging side portions 10 which lead directly to the outlet 7 to form in effect a straight sided funnel 11 in rear of the refuse receiving front portion.

20 A feed pipe 12, which may be connected directly to the city water pressure through a suitable flushometer or which may lead from either a high or a low down tank (not 25 shown) supplies flushing fluid to the inlet 13 at the rear of the flushing rim 2. This rim has a bore 14 substantially horse-shoe shape in form and preferably has a cross-sectional area materially less than the cor- 30 responding area of the feed pipe 12. The ends of the bore adjacent the front portion of the bowl are dependent and open into the bowl in the form of long narrow outlets 15 disposed on opposite sides of the longitudinal 35 medial line. The outlets are arranged in a box 16 forming part of the front wall and extending downwardly for a short distance from the top thereof. The outlets at the lower end of the box are arranged so as to 40 direct the two streams of flushing fluid down and along the curved front wall of the bowl. The sum of the cross-sectional areas of these outlets is materially less than the similar cross-sectional area of the bore 14, or, at 45 least is materially less than the cross-sectional area of the supply pipe 12. A few fluid outlets 17 of relatively small cross-sectional area may be positioned on each side of the center of defilement to cause a thin film of fluid to 50 flow quietly down the curved side walls to meet the edges of the main stream, but these side films are not essential to the operation of the device and may be omitted. In order to form a film of water down the front wall 55 a pair of these small outlets may open from the bore 14 on each side of the main outlets and close to the same. It is desirable that no fluid be fed down the side walls of the funnel part of the hopper, as this would be 60 a waste having no useful result besides any such side feed at this place would seriously interfere with the action of the whirling mass as it passes through the funnel.

The main outlets 15 are substantially rec- 65 tangular in plan and are designed so as to direct a relatively broad and flat stream down each side of the front portion of the bowl. These outlets are separated from each other by means of a partition 18 dividing the box 16 in the longitudinal medial plane of 70 the bowl and acts to maintain the two streams separated for a short distance after they leave the outlets, and to permit the streams to spread over the front portion of the bowl after they have been ejected 75 through the outlets. The partition is preferably wedge shape with the pointed end thereof disposed at or adjacent the top wall of the bore 14. This partition is placed with its longest portion disposed symmetrical 80 relative to the longitudinal medial line of the bowl and has sides of such a depth and of such a length from the top portion of the bowl downward to prevent the union of the two streams until they are at or slightly in 85 advance of the center of defilement.

In order to provide a means for conveniently controlling the projective force of the fluid, a tube 19 preferably of metal, may be removably inserted in the transverse pas- 90 sageway 20 connecting the supply pipe 12 with the bore 14. The bore of this tube may be constricted at two points, as by means of a plug 21, with one of said plugs disposed slightly in advance of each of the side open- 95 ings 22 in the tube leading to the two bores in the rim, but it is obvious that the plugs may be omitted and the flow controlled entirely by varying the extent and character of the openings 22.

In operation the refuse matter is received in the well which is arranged at the center of defilement, in advance of the funnel formed by the converging portions of the wall and in line with the rush of fluid down 100 the front wall. By any suitable means a measured quantity of flushing fluid is admitted from the pipe 12, is forced through the reduced bore 14 in two directions about op- 105 posite sides of the rim and finally forced in the form of a pair of broad liquid shots through the still further reduced outlets. Each of the two main streams flowing from the pair of outlets are directed down the front wall of the bowl and along the bottom 110 and adjacent side to a point of the funnel wall adjacent the outlet and preferably at a point about midway between the center of defilement to the dam. The wedge parti- 115 tion apparently causes the main body of each stream to be somewhat reflected outwardly against the curved sides of the bowl causing the streams to spread out fan shape and causing the outer thinned out edges of each stream momentarily to ride up the 120 sides. The most advanced portion of each stream is reflected inwardly and rearwardly from the funnel walls while the outer edges fold inward and act to choke the outlet mo- 125 mentarily with a whirling plug of fluid. This 130

causes the succeeding portions of the streams to pile up the sides and as the plug is moving through the outlet, the streams flow down the sides toward each other adjacent to the center of defilement while continuing their general movement toward the outlet. The inner edges of the streams meet at the center of the bottom or slightly in advance of the center of defilement and the united lateral streams coact with the next succeeding portion of the stream flowing straight to the outlet to act on the refuse material to lift the same from the bottom into the core of the stream, with not only a lifting but also a pushing action. The slight raise of the bottom from the center of defilement to the dam acts to slightly retard the velocity of flow of the refuse together with the portion of the stream carrying the same and the succeeding portion of the united stream is banked in rear of this mass of moving refuse which forms a wall of relatively great mass to finally sweep the bowl. The outer edges of the united stream as it approaches the restricted passage formed by the funnel slightly rise and fold over inwardly toward the center of the stream, folding with the higher side on top thus eliminating any tendency to splash and forcing all refuse matter both light and heavy toward the core of the flushing. The matter is finally swept over the dam in the form of a whirling cylinder leaving the end portion of the flushing charge in the well in position to receive the next dumping as is usual with devices of this character.

In describing the action of this flushing fluid in the bowl it has been necessary to refer to two streams as if they were entirely separate elements but it is to be understood that reference is merely made to main bodies of fluid which are connected at all points in advance of the partition at least by means of a thin film of fluid.

The total amount of flushing fluid fed at each flushing is preferably controlled by some suitable flushometer which is set to deliver just sufficient fluid to flush the bowl effectively with its usual dumping of refuse, and in this way waste of flushing fluid is minimized. It has been found that four quarts of water under normal city pressure of 17 lbs. has been found sufficient to flush a commercial size bowl of its usual dumping.

Reducing the area of the outlets has the effect of ejecting the flushing fluid forcibly into the bowl thus economically utilizing the full pressure from the feed pipe so as to act on the refuse material not only with the weight of the limited amount of water used but with the maximum flushing force possible with the particular feed pressure used.

Placing the metal tube with its restricted bore in the transverse passageway of the

bowl provides a convenient means for controlling the reduction of area and thus forms in effect a nozzle ejection of the fluid into the flushing rim and provides for a relatively strong projectile force to the fluid. 70

It is to be understood that the statements of movement of the fluid is the theory of operation, as now understood, which best agrees with the observed action of the rushing water in the bowl described, but as the 75 entire operation is confined to less than two seconds the detailed action is too quick for observation.

While I have shown and described, and have pointed out in the annexed claims, certain novel features of my invention, it will be understood that various omissions, substitutions and changes in the form and details of the device illustrated and in its operation may be made by those skilled in the 85 art without departing from the spirit of the invention.

Having thus described my invention, I claim:

1. A closet bowl adapted to receive refuse 90 matter and comprising means for directing a pair of flushing streams toward a point in advance of and adjacent the refuse matter to form a body of moving water at this point, said bowl including side walls, the 95 forward portions of which act on the stream simultaneously to cause the succeeding portion of each of said streams to change their general direction of movement toward each other thereby to meet adjacent the refuse 100 matter to raise the same into the body of moving water, means for momentarily retarding the flow of said refuse and its carrying water and the rear portion of said walls acting on the stream to cause the edges of 105 said stream to turn inward to drown all light or floating refuse matter.

2. A closet bowl having a rear outlet, a bottom terminating in a dam adjacent said outlet and slightly concaved from front to 110 rear to form a well at the center of defilement, outwardly bellied side walls rounding into said bottom to form the central portion of the bowl somewhat elliptical in cross-section, said sides converging toward said outlet to form a horizontally disposed funnel of decreasing cross-sectional area toward said outlet, a pair of flush water outlets at the front portion of the bowl and on opposite sides of the longitudinal medial line of the 115 bowl, said outlets directing the streams along the sides adjacent the bottom toward the walls of said funnel and a wedge shaped partition having its broad end adjacent the outlets for separating the main portions of 120 said streams until they have passed down the front portion of the bowl.

3. A closet bowl having a front wall and a bottom rounding from one into the other, said front wall being provided with a pair 130

- of flush water outlets, a conduit leading to each of said outlets, said outlets being flat and of materially reduced cross sectional area compared with the cross sectional area 5 of the conduits thereby to form ejecting nozzles at the forward end of each conduit, a partition constituting the means for separating said outlets and extending below said conduit in the direction of movement of the 10 streams from said outlets and adapted to maintain said streams separated for a portion of their travel after they have been ejected through said openings, said openings extending lengthwise of the adjacent front 15 wall whereby flat shots of flush water are ejected along the front wall.
4. A closet bowl having the interior portion thereof in the form of an oblate spheroid with a pair of horizontally spaced flush 20 water outlets opening into said bowl and confined to the front portion thereof, said outlets being elongated and adapted to form the water into flat streams and means extending into the bowl for maintaining the 25 streams from said outlets separated while flowing down said wall, a supply pipe leading to the rear of said bowl, substantially all of the water from said pipe being directed equally through said pair of outlets.
5. A closet bowl having a front wall and a shallow bottom rounding from one into the other, said front wall being provided with a pair of flush water outlets, a partition for 30 separating said outlets and extending in the general direction of movement of the streams from said outlets, said partition being in the form of a wedge in plan with the broad end disposed adjacent the outlets.
6. A closet bowl having a relatively long 35 sweeping curved bottom extending from front to rear leading to a rear outlet having its lowest edge placed slightly above the lowest point of said bottom whereby a shallow pool may be formed on said bottom, said bowl having a continuous curved wall with a portion overhanging the bottom and including substantially straight side portions converging toward said rear outlet to form a funnel, 40 and a rounded front portion uniting said side portions, said bowl having a seat with a center of defilement positioned within said rounded front portion and in advance of said converging side walls and means for 45 supplying a main body of flushing fluid to the upper front part of said curved bottom and above the pool, said means comprising two main streams directed toward said funnel.
7. A closet bowl having a relatively long 50 sweeping curved bottom extending from front to rear leading to a rear outlet having its lowest edge placed slightly above the lowest point of said bottom whereby a shallow 55 pool may be formed on said bottom, said bowl having a continuous curved wall with a portion overhanging the bottom and including substantially straight side portions converging toward said rear outlet to form a funnel, and a rounded front portion uniting said side portions, said bowl having a seat with a center of defilement positioned within said rounded front portion and in advance of said converging side walls, means for supplying a main body of flushing fluid to the upper front part of said curved bottom and above the pool, said means comprising two main streams directed toward said funnel, 60 and a rounded front portion uniting said side portions, said bowl having a seat with a center of defilement positioned within said rounded front portion and in advance of said converging side walls, means for supplying a main body of flushing fluid to the upper front part of said curved bottom and above the pool, said means comprising two main streams directed toward said funnel, 65 and a rounded front portion uniting said side portions, said bowl having a seat with a center of defilement positioned within said rounded front portion and in advance of said converging side walls, means for supplying a main body of flushing fluid to the upper front part of said curved bottom and above the pool, said means comprising two main streams directed toward said funnel, 70 and a rounded front portion uniting said side portions, said bowl having a seat with a center of defilement positioned within said rounded front portion and in advance of said converging side walls, means for supplying a main body of flushing fluid to the upper front part of said curved bottom and above the pool, said means comprising two main streams directed toward said funnel, and means for supplying a thin film of water 75 to the front portion of the bowl to prevent splashing from said main streams.
8. A closet bowl having a substantially flat bottom providing a channel for a main flow of flushing fluid, a funnel shaped member forming a continuation of said bottom and leading to a rear outlet, outwardly belled side walls having a portion overhanging said bottom and then rounding into the same and leading rearwardly to the sides 80 of said member, means for forming said main flow comprising two flush water outlets, a partition for separating said outlets, and means for feeding a film of fluid down said side walls to meet the edge of the main 85 stream before it is directed into the funnel shaped member.
9. A closet bowl having a substantially flat bottom providing a shallow channel for a main flow of flushing fluid, a funnel leading from the refuse receiving portion of said bottom to an outlet, said bowl having side walls leading to said funnel, means for directing two main streams of flushing fluid along the side walls of the bowl toward 90 the side walls of the funnel adjacent the outlet, the upper portion of said side walls being curved inwardly to fold the sides of the flow inwardly as it rises on said sides, thereby to dampen any floating refuse and 95 to imprison air within the flow.
10. A closet bowl having a refuse receiving portion and a horizontally disposed funnel portion leading rearwardly therefrom, means in advance of said funnel for causing the flush water to pass in a pair of streams toward said funnel portion in a direction to be deflected by the walls of the funnel portion to assume a vertical whirl through the funnel, a rim providing a seat 100 for said bowl over the receiving portion thereof, said rim providing a pair of conduits for flush water and having outlets disposed in the front of the receiving portion in advance of the funnel portion.
11. A closet bowl having a refuse receiving portion and a horizontally disposed funnel portion leading rearwardly therefrom, the refuse receiving portion having horizontally disposed side portions overhanging 105
- 120
- 125
- 130

the bottom thereof, means for feeding a pair of flushing streams along said bottom into said funnel, the overhanging side portions adapted to act on said stream to inturn 5 the edges thereof whereby said stream is caused to assume a substantially vertical whirl as it passes into the funnel and means for directing a portion of said streams laterally of their general direction of flow to 10 form a wall of flushing fluid in rear of the most advanced portion of the whirling streams.

12. A closet bowl having a transversely disposed passageway in the rear thereof and 15 having a bore leading from said passageway to a flush fluid outlet, a tube adapted to be positioned in said passageway and having an opening in the side thereof adapted to open to said bore, means for supplying a flushing fluid to one end of said tube, said tube having a constriction in the bore thereof positioned between said means and said opening.

13. A closet bowl having a rear outlet, 25 a bottom terminating in a dam adjacent said outlet and slightly concaved from front to rear to form a well at the center of defilement, outwardly bellied side walls rounding into said bottom to form the central portion of the bowl somewhat elliptical in cross-section, said sides converging toward said outlet to form a horizontally disposed funnel of decreasing cross-sectional area toward said outlet, a pair of flush water 35 outlets at the front portion of the bowl and on opposite sides of the longitudinal medial line of the bowl, said outlets directing the streams along the sides adjacent the bottom toward the wall of said funnel and means for separating the main portion of said streams until they have passed down the front portion of the bowl.

14. A closet bowl having a slightly con-

caved and horizontally disposed bottom at its center of defilement and an outlet leading from said bottom at one end thereof, 45 curved sides rounding into said bottom and a water ejecting nozzle positioned above the normal water level on said bottom and disposed adjacent the end of the bottom opposite the outlet co-acting with said curved sides for directing a flushing stream downwardly toward said bottom thereby to raise the refuse off said bottom toward the core of the stream in its passage toward the 55 outlet.

15. A closet bowl having a slightly concaved and horizontally disposed bottom at its center of defilement and an outlet leading from said bottom at one end thereof, 60 said bowl having curved sides leading to said bottom and a water ejecting nozzle positioned above the normal water level on said bottom and coacting with said curved sides for directing a flushing stream relative 65 to said bottom to raise the refuse off said bottom.

16. A closet bowl having a slightly concaved and horizontally disposed bottom at its center of defilement, side walls overhanging the bottom and rounding into the same, and an outlet leading from said bottom at one end thereof, means for directing a flushing stream relative to said bottom to raise the refuse off said bottom and simultaneously to dampen any light floating refuse material and force all refuse toward the core of the stream in its passage toward the outlet.

Signed at New York city, in the county 80 of New York and State of New York, this twenty-third day of November, A. D., 1914.
